UNITED STATES PATENT OFFICE.

GEORGE E. HULSE, OF NEWARK, NEW JERSEY, ASSIGNOR TO THE SAFETY CAR HEATING & LIGHTING COMPANY, A CORPORATION OF NEW JERSEY.

LUMINOUS-FLAME SIGNALING APPARATUS.

Application filed October 26, 1918. Serial No. 259,883.

To all whom it may concern:

Be it known that I, GEORGE E. HULSE, a citizen of the United States, residing at Newark, in the county of Essex and State 5 of New Jersey, have invented certain new and useful Improvements in Luminous-Flame Signaling Apparatus, of which the following is a full, clear, and exact description, such as will enable others skilled in 10 the art to which it appertains to make and use the same.

This invention relates to signaling apparatus which involves the combustion of gas to produce a luminous signal flame, and 15 with respect to its more specific features to buoys, beacons, stake-lights, light-ships and lighthouses.

In the art of signaling employing luminous flame as the light source, attention has 20 been devoted rather to the projecting and controlling of the radiated light than to the character of the luminous flame itself. The normal luminous flame such as produced by combustion of an efficient hydro- 25 carbon gas has been, unconsciously perhaps, accepted as a standard, variable within cer- tain limits, dependent upon the contemplated use, whereas a fruitful field: to wit, the 30 quality of the radiated light and its coopera- tion with certain projecting devices seems to have been almost wholly neglected, if not unrecognized. The present invention in- 35 volves on the one hand, recognition of the qualities of different lights, their different physiological effects and their different co- 40 operative effects with projectors, as lenses or other refracting media, and on the other hand the provision of a practical means by 45 which the various factors of the first hand may be taken advantage of and controlled to the end that a luminous flame signaling apparatus of high radiant and mechanical efficiency under difficult practical conditions may result. An embodiment of the invention 50 will first be described, and certain ad- vantageous results will be pointed out there- after.

One of the objects of the invention is the provision of a practical device for automatically supplying hydrocarbon gas and free oxygen to a burner for the production of a highly luminous signal flame.

Another object is the provision of a simple device for automatically controlling the de-

livery of different gases to a burner inter- 55 mittently and in timed relation.

Still another object is the provision of a practical apparatus for the production of a 60 flashing flame formed by combustion of free oxygen and a hydrocarbon gas in which the supply of free oxygen to the burner is controlled by the supply of hydrocarbon gas thereto.

Another object is the provision of a flash- 65 ing buoy of practical and efficient construc- tion, relatively inexpensive, and adapted to subserve the vicissitudes of use in which the light is produced by combustion of free oxy- gen with hydrocarbon gas.

Still another object of the invention is 70 the provision of a practical device to im- 75 prove the effectiveness of flame signal lights, to the end that the visibility of such lights for short distances may be retained and their efficiency enhanced and yet the visibility of the light for long distances be increased.

Another object of the invention is the provision of a simple apparatus in which a closer approach to perfection of focusing 80 of the light source or energy radiator, when derived from burning gas, relative to prismatic refractors, as usually employed in light-houses, buoys, etc., may be attained.

Another object is the provision of a simple device for the production of an an- 85 nular luminous hydrocarbon flame of a rela- tively high temperature in which the tem- perature radiations generally normal to the annulus are substantially uniform around the annulus and concentrated in a relatively 90 short smokeless annular flame.

Still another object is the provision of an apparatus of the character referred to in 95 which the intensity of a flame of hydro- carbon gas is increased without necessarily increasing the candle power of the flame and while maintaining a fixed rate of flow of the hydrocarbon gas to the burner.

Other objects will be in part obvious and in part pointed out hereinafter.

The invention accordingly consists in the features of construction, combinations of elements and arrangement of parts which will be exemplified in the construction hereinafter set forth, and the scope of the appli- 105 cation of which will be indicated in the following claims.

In the accompanying drawings forming

part of this specification and wherein similar reference characters refer to similar parts throughout the several views.

Fig. 1 is a site elevation of the invention 5 as embodied in a buoy, parts of the apparatus being shown in section and partly broken away for clearer disclosure;

Fig. 2 is a perspective view showing certain interior construction of one of the flashing chambers;

Fig. 3 is a vertical section through this flashing chamber;

Fig. 4 is a plan view of this flashing chamber surmounted by the burner.

Fig. 5 is a side elevation of Fig. 4, the burner and some associated parts being illustrated in vertical section;

Figs. 6, 7, 8 and 9 illustrate various details of the burner; and

Fig. 10 is a side elevation of the buoy body with the tower broken away.

The disclosure is herein made in connection with a light buoy, being a simple example of signals of the character above referred to. The numeral 1 indicates the body of the buoy, which may be a floating body and anchored in position by means of a chain 2. The numeral 3 indicates a tower, being a metallic skeleton frame fastened to the upper portion of the body of the buoy and which may have, at a suitable point, a platform upon which an attendant may stand. Fastened to the upper portion of the tower 3 is a pressure regulator 4, comprising cylindrical, lateral walls supporting a lantern including a curved, as cylindrical, prismatic refractor, as a Fresnel lens 5, a protective cage 6 and a chimney 7. The upper wall of the chamber of the regulator 4 comprises a web, or inwardly projecting flange 8, upon which is mounted a flashing chamber 9 and a burner 10, as more specifically hereinafter described. In the body of the buoy are separate sources of supply, 45 for the combustible materials for furnishing the luminous flame, this body being divided into two compartments, or reservoirs, one, indicated by the numeral 11, for the reception of compressed hydrocarbon gas, as 50 Pintsch gas, and the other, indicated by the numeral 12, for the reception of gaseous; that is, free oxygen, in a compressed state. The gases from the reservoirs 11 and 12 are conducted through conduits "in parallel," as 55 distinct from conduits "in series," i. e., they are led through independent, or separate conduits to the burner 10, and in the present embodiment the conduit for the hydrocarbon gas includes the pipe 13, the regulator chamber 4, into which this gas is led from the pipe 13, the pressure, or flashing chamber 9, to which the gas is led from the regulator chamber, and a pipe through 60 which communication is established between the flashing chamber and the burner. The

conduit for the oxygen gas comprises the pipe 14 leading from the reservoir, a pressure regulator 13', similar to the regulator 4, into which the oxygen is lead from the pipe 14, a chamber, as pressure chamber 108 70 to which the oxygen is conducted by a pipe 14', controlled by valve 12', and a pipe 15 which leads from the chamber 108 to the burner.

The objects of the regulator chambers 4 75 and 13' are to reduce the pressure of the hydrocarbon gas and oxygen in the reservoirs to those suitable for the operation of the flashing chambers and the burner. In the present specific embodiment, each conduit includes devices to control delivery to the burner.

On its way to the pressure regulator 4 from the reservoir, the hydrocarbon gas may be screened. From the pipe 13 it passes through a valve device 16, from which it emerges into the regulating chamber 4. The upper wall of this chamber is provided with a flexible diaphragm 17, depending from which is a link 18 connected to a pivoted 80 arm 19 of a valve which opens when the pressure in chamber 4 falls below a predetermined pressure and closes when the pressure exceeds the predetermined pressure. A spring 20 serves to determine this pressure. The numeral 21 indicates a pipe providing 85 an exit opening from the regulating chamber for the hydrocarbon gas and conducting such gas to a valve fitting 22, whence such gas may be conveyed directly to the burner or indirectly thereto after passing through the flashing chamber 9. In Fig. 4 the valve fitting 22 is illustrated in plan as supplied by the pipe 21 from the regulating chamber. On the fitting 22 a pipe 23 leads 90 horizontally around the outside of the flashing chamber 9 and then extends upwardly, as at 24, whence it communicates with the burner. A hand-operated screw valve 25 enables the pipe 23 to be shut off from the 95 valve fitting. Also extending from the valve fitting 22 and horizontally partially around the flashing chamber 9 is a pipe 26 which, or an extension of which, enters through the side of the flashing chamber and communicates with an inlet port 27 of such chamber (Fig. 3). The numeral 28 indicates an outlet port for the flashing chamber. Hydrocarbon gas emerging through said port passes through the passageway 29 and pipe 100 30, which latter communicates in turn with the pipe 24 leading to the burner. A hand-operated screw valve 31 serves to cut off communication between the valve fitting 22 and the pipe 26 when desired. A third pipe, 105 namely pipe 32, leads from the valve fitting 22 directly to a pilot port 33, (Fig. 4) in close proximity to the burner ports for the exit of the hydrocarbon gas and oxygen, for the purpose of providing a permanent 110 120 125 130

igniter or pilot flame, for initiating the combustion at the burner. A screw valve 34 may be employed to control the supply of hydrocarbon gas to the pilot port 33, as desired. If reference be made to Fig. 4 it will be seen that by closing the valve 31 the hydrocarbon gas will be shut off from the flashing chamber, and when the valve 25 is open said gas will pass directly to the burner 10 through the pipes 23 and 24; or the valve 25 may be closed and the valve 31 open, whereupon the hydrocarbon gas will pass through pipe 26 into the flashing chamber, thence out of the flashing chamber and 15 through the pipes 30 and 24 to the burner.

Means, as a valve-device, is employed to control the entry and exit of the hydrocarbon gas into and out of the pressure, 20 flashing chamber 9 and thereby control the delivery of this gas to its port in the burner and effect an intermittent emission of such gas from the burner port, to the end that a flashing light may be provided, the jet of hydrocarbon gas from the burner being ignited 25 from the pilot, as will be understood. In the present embodiment this means comprises a rock shaft 40 pivotally supported in conical bearings on the inner faces of 30 brackets 41 upstanding from the bottom 42 interiorly of an expansible and contractible chamber, the flashing chamber, one of these bearings being adjustable, as indicated at 43. The rock shaft 40 has two arms, 44 and 45 respectively, supporting valves 46 35 and 47 adapted to open and close the flashing chamber inlet port 27 and the flashing chamber outlet port 28, respectively, these valves being so disposed that when one of the ports, as 27, is closed, the other port, 28, is open and vice versa. The valves 27 and 40 45 28 are opened and closed by variation in volume of the flashing chamber 9. At a suitable point in its length rock shaft 40 is provided with a lug 48. Above the rock shaft 40 and supported in the brackets 41 in a manner similar to that of the rock shaft 40, is another rock shaft, 49, having 50 two arms 50 and 51 adapted to co-operate with lug 48 to rock the shaft 40 in opposite 55 directions. The province of the arms 50 and 51 is to cooperate with the lug 48 and, in the present embodiment, to strike said lug and thereby rock the shaft 40 in one direction or the other at proper times, and in order 60 that adjustment may be provided for, tappet pins 52 and 53 are threaded into the arms 50 and 51 and serve as means for directly contacting with the lug 48. The upper rock shaft 49 has arms 54 and 55 at 65 right angles thereto, the ends of each of which are connected motors, as coil springs 56, 57, which are normally under compression when the device is in operative condition, so that they are always in condition 70 to rotate the shaft 49 in one direction or the

other when properly set. In order to equalize the operation of the springs 56 and 57, they are connected to pins 58 and 59 carried by a yoke 60, the pins 58 and 59 having sliding action in supporting brackets 70 61 and 62. Fast to the upper rock shaft 49 of the motor-operated valve-device-striker is an arm or plate 63 between the two points, 64 and 65, of a forked lever or oscillatory double acting tappet fulcrumed on a bracket 75 66 upstanding from the bottom wall of the flashing chamber, the opposite end of the forked lever comprising an arm 67 disposed between knife edged bearings 68 and 69 of clamps 70 and 71 adjustably fastened to a 80 stem 72 depending from a flexible dia-phragm 73 forming the upper wall of the flashing chamber and adapted to be energized by the pressure of gas in pressure chamber 9 to operate said double acting 85 tappet. The numeral 74 indicates a guide lever for the stem 72, said lever being pivoted to bracket 75, as illustrated, and the stem 72 being connected to the guide lever 74 by means of an extension 76 passing through 90 a slot in the lever 74, a pin 77 operating to prevent disconnection. This pin may be less in length than the slot, so that, upon registering therewith, the parts may be separated. The flexible diaphragm 73, which 95 may be made of leather, may be held in place by an annular plate 78 bolted to a flanged side wall 79 of the flashing chamber and a thin rigid metallic plate 80, which may be of brass, may be employed to confine the expansion of the diaphragm in an upward direction and restrict it beyond a certain limit to a relatively small central portion thereof. The numeral 81 indicates a coil spring resting upon the central portion of the dia- 100 phragm 73 and operating against a yoke 82 bolted to the plate 78. A top or cover 83 is employed to enclose the spring 81 and its yoke and serve as a support for the burner hereinafter described. To assist in 105 seating the valves 46 and 47, light compression coil springs 84 may be employed, these springs being connected in pairs to said valves and to brackets 85.

The operation of the flashing chamber 9 110 may now be described. The hydrocarbon gas from the regulator 4 enters the flashing chamber through the pipe 26, assuming the inlet valve 46 to be open. The diaphragm 73 rises, the chamber thus expanding, as the gas continues to enter, and lifts the stem 72, which latter in turn raises the arm 67 and depresses the forked end of the lever or double acting tappet, and eventually the threaded pin in the tine 64 of this lever 115 strikes the arm 63, thus rocking the upper shaft 49 in a direction to cause the pin 53 to approach the lug 48. The tendency of the springs 56, 57 and 84 when the outlet valve 47 is closed is to retain the shaft 40 120

125

130

in position to keep the port 28 closed, but the rocking of the shaft 49 as just explained eventually reverses the operation of the springs 56 and 57, so that when the dead center is passed said springs 56 and 57 operate as motors, and quickly rock the shaft 49 so as to cause the pin 53 to strike the lug 48, thus quickly opening the port 28 and closing the port 27, whereupon gas will cease 10 to enter the flashing chamber, and the gas therein will pass through the port 28 to the burner and be assisted in its passage thereto by the expansion of the spring 81, which, having had energy stored therein by pressure of gas, will depress the diaphragm 73, thus causing the chamber to contract, and force the gas to the burner. As the stem 72 descends a reverse operation of the forked lever will ensue and the lower fork 65 will 15 contact with the arm 63 and eventually the shaft 49 will be snap-rocked in the opposite direction to cause the inlet valve 46 to again open and the outlet valve 47 to again close. By adjusting the pins 52 and 53 the instant 20 of operation of the valves 46 and 47 may be predetermined, and it may be noted that the forked lever or double acting tappet referred to may be provided with similar pins for determining the time of operation of the 25 rock shaft 49. Thus the hydrocarbon gas will be automatically supplied to and cut off from the burner and the supply and cutting off thereof will be quickly accomplished so that the flame at the burner will be instantaneously extinguished or instantly supplied 30 for ignition, as the case may be.

In the present embodiment the burner is supported upon the top 83 of the flashing chamber and comprises a metallic frame, in 40 the present instance made in upper and lower separable parts 90 and 91, of substantial construction and providing an interior hollow portion. The upper part comprises a vertical cylindrical opening 92 having a 45 removable cylindrical post 93 threaded into the frame part and composed preferably of phosphor-bronze. Surrounding the post is a phosphor-bronze cylindrical shell 94 having a tapered portion 95 which may be seated in the tapered lower part of the opening 92 and drawn down and held firmly therein by a shoulder 96 on the post 93 co-operating with the base portion of the shell, as illustrated. At its upper cylindrical portion the shell 94 is spaced both 50 from the cylindrical wall of the post 93 and the interior cylindrical wall of the opening 92, thus providing two concentric annular closely adjacent emission ports 96 and 97, 55 the former for the emission of the hydrocarbon gas and the latter for the emission of free oxygen. The shell 94 is apertured, as at 98, adjacent its base, and these apertures register with an annular recess 99 in 60 the frame portion 90. The hydrocarbon

gas, being supplied to the recess 99 through the passageways 100 and 101 controlled by the valve 102, will find its way to the port 96 and emerge therefrom as an annular jet. Also surrounding the shell 94 is another 70 annular recess 103 sealed from the recess 99 by the inwardly projecting flange 104 of the frame part 90, but directly communicating with the annular port 97. Passageways 105 and 106 controlled by valve 107 lead to the 75 annular recess 103 and are supplied with free oxygen through the pipe 15 from an oxygen controlling chamber 108. The pilot port 33 is located close to the outer port 97, and communication with a lateral passage 80 108' in the frame part 90, the passage 108' in turn communicating with the pipe 32.

The upper and lower frame parts 90 and 91 of the burner are hollowed out, as previously referred to, and their flanged portions 109 and 110 are bolted together, a flexible diaphragm 111 which may be of leather, being secured therebetween and dividing the hollow interior into two expandable and contractible chambers, the lower chamber receiving oxygen from the reservoir 12 through the pipes 14 and 14', the oxygen gas having its pressure reduced in another regulator, similar to the regulator 4, and situated therebelow as indicated 90 at 13'. The chamber 108 is adapted to control the delivery of free oxygen to the burner port 97, and in the present embodiment delivers it intermittently, or in flashes. The numeral 112 indicates an outlet port 95 from the oxygen chamber 108 to the burner port 97 controlled by valve 113 carried by pivoted arm 114, in turn pivotally connected to the central portion of the diaphragm 111, which provides a pressure operated valve-operating member, the construction being such that, upon expansion of the chamber 108, as by a lifting of the diaphragm 111, thus increasing the volume 100 of this chamber, the valve 113 will be closed. A spring 115 co-operates with the lever 114 and tends to close the valve and lift the diaphragm 111 and oppose operation of diaphragm 111 to open discharge valve 113. When the volume of the chamber 108 is decreased as by a depression of the diaphragm, 115 valve 113 will be opened and permit flow of oxygen to the burner.

The upper chamber of the burner frame is indicated by the numeral 116, the diaphragm 111 being a common wall between the two chambers, and the hydrocarbon gas on its way to the burner is permitted to enter the upper chamber 116 through the port or passageway 117 in communication with the pipe or passageway 24 leading the hydrocarbon gas from the flashing chamber. It will be perceived that when the hydrocarbon gas acquires sufficient pressure in the upper chamber 116 it will depress the 120 125 130

diaphragm 111 and open the oxygen outlet valve 113 so as to permit the free oxygen to flow through the pipe or passageway 15 to the port 97 of the burner.

- 5 The burner 10 is so disposed that the luminous flame formed by the combustion of the hydrocarbon gas and free oxygen is as close as possible to the focus of the refracting projecting Fresnel lens. In the 10 present embodiment the Fresnel lens is generally cylindrical, and it will be seen that the burner produces an annular flame concentric with the lens and approximately at the focus of the lens.
- 15 The reservoirs 11 and 12 will be filled with the respective gases which should be under sufficient pressure to effectively feed and in sufficient amount to supply the gases for a considerable period of time. The hydrocarbon 20 gas will first have its pressure reduced to an efficient working pressure by the pressure regulator and thence will enter the flashing chamber through the port 27. As the gas continues to enter this gas chamber, the 25 discharge valve 47 is in closed condition, and the wall 73 will be moved in a direction to increase the volume of this chamber and thereby, through the instrumentalities explained, close the cut off valve 46 and simultaneously open the cut off valve 47. Thereupon the wall 73 will move in the opposite direction, thus decreasing the volume of this chamber, and pressing gas therefrom while valve 46 is closed through the 30 same instrumentalities, will then open the valve 46 and simultaneously close the valve 47, so as to permit a new supply of gas to enter from the regulator chamber during closure of valve 47. Hydrocarbon gas 35 from the flashing chamber 9 will be conducted by the pipe 24 to the burner and also to the chamber 116, the movable diaphragm 111 of which latter is exposed to the pressure of this gas. The diaphragm, or member, 111 is also exposed to the pressure of the oxygen 40 gas in the gas or flashing chamber 108, and it will be perceived that the diaphragm 111 will, within certain limits, take up a position dependent upon the pressures on the opposite 45 sides thereof. As the pressure in the chamber 116 increases the diaphragm 111 will be depressed thus increasing the volume of chamber 116 and decreasing the volume of chamber 108, and the oxygen cut off valve 50 55 60 65 70 75 80 85 90 95 100 105 110 115 120 125 130 135

opens practically immediately. When the valve 47 closes, the oxygen valve at once closes, the burner port serving as an exit for the hydrocarbon gas in the chamber 116, and providing for an immediate reduction of 70 pressure above the diaphragm 111.

Thus the oxygen delivery valve 113, is operated in timed relation to the valves in the flashing chamber 9, and the jets of the two gases at the burner are produced or cut 75 off practically simultaneously, and at regular intervals. By setting the screw valve 31, the interval between flashes may be regulated as desired.

By closing the valve 31, the hydrocarbon 80 gas may be cut off from the flashing chamber 9, and on opening the valve 25, such gas will go directly to the burner via the conduits 23 and 24, and to the pilot via the conduit 32. Delivery of oxygen through pipe 14 may 85 be controlled and, if desired, cut off, by operating the valve 118 (Fig. 1).

It will be observed that the pressure of gas in the hydrocarbon conduit energizes the pressure chamber, or flashing chamber, 9, 90 the gas acting directly to raise the diaphragm, or wall, 73, and to store energy in the spring, or motor, 81. As the diaphragm rises it eventually operates the double acting tappet in one direction, and sets the motors, or springs 56 and 57, into position where they will suddenly expend some of their energy to cause the valve operator arm 51 to strike the lug 48 and thereby quickly open valve 47 and simultaneously quickly close valve 46. 100 As the diaphragm lowers under the influence of the spring 81, a reverse operation occurs to that above described, and the valve 46 is quickly closed and the valve 47 quickly opened. From the pressure chamber 9, gas 105 is discharged past valve 47 to the burner port, or discharge port of the hydrocarbon conduit, and also may enter the pressure chamber 116, the diaphragm, or valve operating member 111, of which is exposed on one side to the pressure of the gas in the hydrocarbon conduit discharged from chamber 9, and on the other side to the pressure of the gas in the oxygen conduit, of which latter conduit the pressure chamber 108 110 forms a part, in the present embodiment. One of the purposes of the pressure chamber 108 is to furnish elastic opposition to the operation of the valve operating member, or diaphragm 111, under the pressure of the 115 gas in the hydrocarbon conduit, and it will be perceived that by providing a chamber with the movable diaphragm, as the chamber 108 with the member 111, a means to offer such elastic opposition results. In the 120 embodiment disclosed it will also be observed that the chamber 108 is continuously open for reception of gas from the conduit pipe 14', so that the force of opposition due to pressure of gas is substantially constant. 125 130 135

When the discharge valve 113 of the oxygen pressure chamber 108 opens, by depression of the valve controlling device, or diaphragm 111, the oxygen flows through the chamber 108 and out of the discharge port 112 to the burner. It will be observed therefore that the discharge valve of oxygen chamber 108 is energized to open by a preponderating pressure in the hydrocarbon conduit as compared with the force of opposition furnished, in the present embodiment, by the gas chamber 108, or a spring, as at 115, or both. In the present embodiment the valve lever or arm 114 is pivotally connected to member 111, upward movement of the member positively closing this valve. Of course the spring alone might be relied on to effect closing of this valve. It will be perceived therefore that the variable volume pressure chamber 108 is adapted to yieldingly oppose variation of volume of the variable volume pressure chamber 116 from a predetermined volume, and that the valve 113 operates as a flow control device and is operated in response to variation of pressure in the chamber 116, and at the same time and at like intervals as the valve device for the chamber 9.

Adverting to that phase of the invention which has for its object the production of a light which shall have high efficiency visibility for short distances and in such media as fog, and shall have its visibility for long distances increased, as compared with the results attained by a luminous flame resultant from combustion in air, it may be stated that the ordinary air burning flame, of its own nature, has relatively, little distance visibility, because it does not contain waves of sufficiently high frequency in sufficient amount. For long distance visibility waves of relatively high frequency are required, and the high temperature flame of the present invention contains abundance of such waves, so that its visibility for long distances is very marked. At the same time the flame of the present invention contains waves of relatively low frequency and consequent greater length, such as orange-yellow, and inasmuch as these longer wave lengths penetrate fog better than the shorter wave lengths, the flame of the present invention possesses high efficiency visibility both for long distances, short distances and the penetration of fog, and is adapted to a wider range of use than a light which possesses but one of these characteristics. As the limits of visibility the eye is greatly more sensitive to high frequency light than to low frequency light.

Relative to the greater perfection of focusing attained by the present flame, it is to be noted that the effect of combustion with free oxygen is to greatly decrease the height

of the flame, besides increasing its temperature and the average frequency of radiation. One consequence is that a closer approximation to theoretical focusing relative to the refracting lens 5, is attained, due to the fact that the flame is shorter as compared to an air burning flame. Another and most important consequence is that, in conjunction with the refractor, the visibility for a distant point is increased, because, though the light contains waves of different frequencies, these frequencies are sufficiently close to each other to be refracted more nearly alike. The effect of a refractor is to deflect the higher frequencies more than the lower, and it is apparent that low frequency light will be refracted in one direction and high frequency in another. In the air burning flame the frequencies are all relatively low, and the limit of visibility short. In the arc light the frequencies may be considered high, and the limit of visibility long. The present flame may be considered to occupy an intermediate position in the scale of frequency, so that more of the light is deflected the same amount and hence the visibility is increased both for long and short distances because more of the light is given the same or approximately the same direction by the refractor. And the shorter the flame, and consequent closer approach to perfection of focusing, the closer will the light be refracted in the same or parallel paths.

Furthermore it is a physiological fact that the shorter wave lengths are more quickly perceived by the eye. Hence in quickly scanning the horizon for a light, moving the eyes back and forth, the luminous flame of the present invention will make its impression on the eye under conditions which might cause the air burning flame to escape notice. This is especially true of a flame which appears at intervals only, as a flashing flame.

It will be observed that, not only are the gas and oxygen ports of the burner such as to produce an annular flame by combustion between the gases of the annular jets, but that the oxygen port supplies the oxygen initially to the base, or lower portion, of the jet issuing from the hydrocarbon gas port, and outside the latter port, the exit orifices of these ports being in the same horizontal plane, flush with the top of the burner in the present embodiment. The free oxygen is therefore supplied uniformly around the annular jet of hydrocarbon gas, and flows upwardly alongside the gas jet so as to act to the full height of the flame, as it were. Thus not only the central and upper part of the flame is given increased luminosity, but the base as well whereas an air burning flame is of widely varying

luminosities from its base to its tip, being very low at its base. By the present construction the flame is intensely luminous from its base to its tip, and appears as a band of light in which the temperature radiations generally normal to the annulus are substantially uniform around the annulus and concentrated in a relatively short smokeless flame.

10 Adverting to the construction of the body of the buoy and the reservoir for the gases, it will be observed that, in the present embodiment, the body 1 comprises a large hollow body portion which is generally circular in cross section, and has an interior axially disposed chamber 119, the lateral wall of which extends below the bulge of the oxygen chamber 12, and is closed at its bottom. In this chamber 119 may be deposited a flask of the compressed hydrocarbon gas employed, this flask providing the hydrocarbon gas reservoir previously referred to. Suitable means may be employed to securely hold the flask in the chamber 119. The tower 3 will of course be of such construction or size as to admit of the convenient deposition and removal of this flask.

It will be observed that the annular jet of hydrocarbon gas issuing from the burner 10 is initially of fixed diametrical dimension. The edges of the orifice of the port 96 are in the same horizontal plane, so that even though the pressure of emission varies the diameter of the annular jet remains the same. Thus the flame substantially preserves a constant relation, laterally, relative to the lens 5. By setting the valves 31 and 102, the rate of emission of the hydrocarbon gas from the burner may be regulated and will remain substantially fixed for a certain setting, and this, in conjunction with the fixed lateral dimension makes for accuracy of focusing. The resultant flame, though not all theoretically perfectly focused, will preserve its size and its relation to the lens 5 to a marked degree so that dependence may be placed upon the projection of the different wave lengths in approximately the same or parallel paths.

50 Thus by the above described construction are accomplished, among others, the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific

features of the invention herein described, and all statements of the scope of the invention which, as matter of language, might be said to fall therebetween.

Having described my invention, what I claim as new and desire to secure by Letters Patent is—

1. In an apparatus of the character described, in combination, a burner, two sources of supply of gas, separate conduits leading from said sources directly to said burner, devices adapted to control delivery through said conduits to said burner, comprising means controlled by a predetermined pressure of gas in one conduit adapted to operate one of said devices to open communication to the burner, and means whereby passage of said gas to the burner is adapted to operate another of said devices to open communication through said other conduit to the burner.

2. In an apparatus of the character described, in combination, a burner, two sources of supply of gas, separate conduits leading from said sources to said burner, devices adapted to control delivery through said conduits to said burner comprising means controlled by a predetermined pressure of gas in one conduit adapted to operate one of said devices to open communication to the burner, and means whereby said passage of said gas to the burner is adapted to operate another of said devices to open communication through said other conduit to the burner, said last mentioned means being responsive to a difference in pressure between the gas on its said passage to the burner and that in the other conduit.

3. In an apparatus of the character described, in combination, a gas chamber variable in volume, inlet and outlet valves for said chamber operable by variation of volume of said chamber, the one by increase and the other by decrease of volume of said chamber, a second gas chamber "in parallel" with said first mentioned chamber, a valve for said second chamber, and operating means for said latter valve differentially responsive to pressures in said chambers to permit flow of gas from said second chamber simultaneously with flow from said first chamber.

4. In an apparatus of the character described, in combination, a gas chamber comprising a wall movable to vary the volume thereof, inlet and outlet valves for said chamber, means whereby movement of said wall in one direction opens one of said valves and closes the other, a second gas chamber comprising a wall movable to vary the volume thereof, an outlet valve for said second chamber, means whereby movement in opposite directions of said wall of the second chamber effects closing and opening of the valve thereof, and means adapted to

effect the movements of the valves of one chamber in timed relation to that of the other at like intervals.

5. In an apparatus of the character described, in combination, a gas chamber comprising a wall movable to vary the volume thereof, inlet and outlet valves for said chamber, means whereby movement of said wall in one direction opens one of said valves and closes the other, a second gas chamber comprising a wall movable to vary the volume thereof, an outlet valve for said second chamber, means whereby movement in opposite directions of said wall of the second chamber effects closing and opening of the valve thereof, and means adapted to effect the movements of the valves of one chamber in timed relation to those of the other comprising a third chamber adapted to communicate with said first chamber, and to which and said second chamber the movable wall of the latter is common.

6. In an apparatus of the character described, in combination, a burner having two independent closely adjacent gas ports, two sources of gas pressure, and conduits adapted to independently conduct the gases to the respective ports, one of said conduits comprising a chamber and means adapted to intermittently deliver gas thereto and therefrom, and the other conduit, comprising a chamber and pressure controlled means adapted to intermittently deliver gas therefrom synchronously with the delivery from said other chamber.

7. In an apparatus of the character described, in combination, a burner having two independent closely adjacent gas ports, two sources of gas under pressure, and conduits adapted to independently conduct the gases to the respective ports, one of said conduits comprising a chamber and means adapted to intermittently deliver gas thereto and therefrom, and the other conduit comprising a chamber and means adapted to intermittently deliver gas therefrom synchronously with the delivery from said other chamber, said last mentioned chamber comprising a movable wall, an outlet valve adapted to be operated by movement of said wall, and a conduit adapted to establish communication between said first mentioned chamber and the exterior face of said movable wall.

8. In a device of the character described, in combination, a plurality of conduits arranged in parallel, pressure chambers communicating with said conduits, means associated with said chambers to cause simultaneous intermittent flow of gas in both of said conduits, said means including a valve member closing one of said chambers against entry of gas during discharge therefrom, and vice versa, a rock shaft operatively connected to said valve member, a quick-acting spring motor connected to said rock shaft

and pressure operated means connected to said rock shaft to set said motor for quick operation in either direction.

9. In a device of the character described, in combination, a pressure chamber, means for closing said chamber against entry of gas during discharge therefrom, and vice versa, including a valve member, a quick-acting motor operatively connected to said valve member, pressure operated means connected to said valve member to set said motor for quick operation in either direction, and resilient means for holding said valve member in operated position.

10. In a device of the character described, in combination, two conduits in parallel, a pressure chamber through which gas in one conduit flows, maintained at substantially constant gas pressure and having a delivery control device acted on differentially by said pressure and by gas pressure in the other conduit to cause simultaneous intermittent delivery of gas from both of said conduits.

11. In a device of the character described, in combination, two conduits in parallel, and means adapted to effect intermittent delivery of gas thereby, including a pressure chamber, through which the gas in one conduit flows, having a continuously open entry for gas and a controlled discharge, said chamber including a device, movable under the difference between the effective pressure thereon in the chamber and that in the other conduit, to control said discharge.

12. In a device of the character described, in combination, two gas conduits in parallel, means adapted to supply said conduits with gas under pressure, and gas operated variable volume pressure chambers adapted to cause simultaneous intermittent flow from said conduits and to communicate with each other.

13. In a device of the character described, in combination, two gas conduits, means adapted to supply said conduits with gas under pressure, gas operated variable volume pressure chambers adapted to cause intermittent flow in said conduits and to communicate with each other, and a substantially constant pressure variable volume pressure chamber adapted to yieldingly oppose variation of volume of one of said pressure chambers from a predetermined volume.

14. In a device of the character described, in combination, two gas conduits in parallel, means adapted to supply said conduits with gas under pressure, gas operated variable volume pressure chambers adapted to cause intermittent flow in said conduits and to communicate with each other, and a substantially constant pressure variable volume pressure chamber communicating with one of said conduits and adapted to yieldingly oppose variation of volume of one of said

other pressure chambers from a predetermined volume.

15. In a device of the character described, in combination, two gas conduits in parallel, 5 means for separately supplying said conduits with gas under pressure, gas operated variable volume pressure chambers adapted to cause intermittent flow in said conduits and to communicate with each other, means 10 adapted to close one of said pressure chambers against entry of gas during discharge of gas therefrom and vice versa, and a substantially constant pressure variable volume pressure chamber adapted to yieldingly oppose variation of volume of one of said other pressure chambers from a predetermined volume.

16. In a device of the character described, in combination, two gas conduits, means 20 adapted to supply said conduits with gas under pressure, gas operated variable volume pressure chambers adapted to control flow in said conduits, and a third variable volume pressure chamber through which the gas in one conduit flows adapted to oppose increase of volume of one of said other chambers.

17. In a device of the character described, in combination, two gas conduits, means for 25 separately supplying said conduits with gas under pressure, gas operated variable volume pressure chambers adapted to control flow in said conduits, said chambers being in communication with each other through one of said conduits, and a third variable volume pressure chamber through which the gas in one conduit flows adapted to oppose increase of volume of one of said other chambers.

18. In a device of the character described, 30 in combination, two gas conduits in parallel, gas operated variable volume pressure chambers communicating with one of said conduits and adapted to cause intermittent flow in said conduits, and a third variable volume pressure chamber through which the gas in one conduit flows adapted to oppose increase of volume of one of said other chambers.

19. In a device of the character described, 35 in combination, two gas conduits in parallel, means adapted to supply said conduits with gas under pressure, a first and a second gas operated variable volume pressure chamber through which the gases in the conduits flow, respectively, adapted to cause intermittent flow, respectively, adapted to cause intermittent flow, means adapted to close the first chamber against entry of gas during discharge of gas therefrom, and vice versa, and a third variable volume pressure chamber adapted to receive gas from said first chamber and thereby cause variation of volume of said second chamber.

20. In a device of the character described, 40 in combination, two gas conduits in parallel, means adapted to supply said conduits with

gas under pressure, a first and a second gas operated variable volume pressure chamber through which the gases in the conduits flow, respectively, adapted to cause intermittent flow, means adapted to close the first 70 chamber against entry of gas during discharge of gas therefrom, and vice versa, and a third variable volume pressure chamber adapted to receive gas from said first chamber and thereby cause variation of volume 75 of said second chamber, said second chamber being constantly open for reception of gas.

21. In a device of the character described, in combination, two gas conduits in parallel, means adapted to supply said conduits with 80 gas under pressure, a first and a second gas operated variable volume pressure chamber through which the gases in the conduits flow, respectively, adapted to cause intermittent flow, means adapted to close the first chamber against entry of gas during discharge of gas therefrom, and vice versa, and a third variable volume pressure chamber adapted to receive gas from said first chamber and thereby cause variation of volume of said 85 second chamber, said third chamber communicating with the discharge port of the conduit.

22. In a device of the character described, in combination, two gas conduits in parallel, 90 means adapted to supply said conduits with gas under pressure, a first and a second gas operated variable volume pressure chamber through which the gases in the conduits flow, respectively, adapted to cause intermittent flow, means adapted to close the first chamber against entry of gas during discharge of gas therefrom, and vice versa, and a third variable volume pressure chamber adapted to receive gas from said first chamber and thereby cause variation of volume of said 95 second chamber, said second mentioned means including a valve-device, a motor-operated valve-device striker, and a device energized by pressure of gas to set 100 said striker in action.

23. In a device of the character described, in combination, two gas conduits in parallel, 105 means adapted to supply said conduits with gas under pressure, a first and second gas operated variable volume pressure chamber through which the gases in the conduits flow, respectively, adapted to cause intermittent flow, means adapted to close the first chamber against entry of gas during discharge 110 of gas therefrom, and vice versa, and a third variable volume pressure chamber adapted to receive gas from said first chamber and thereby cause variation of volume of said second chamber, said second mentioned 115 means including a valve-device, a motor-operated valve-device striker, and an oscillatory double acting tappet to set said striker in action.

24. In a device of the character described, 120 125 130

- in combination, two gas conduits in parallel, two pressure chambers, one through which the gas in one conduit flows, and the other adapted to communicate with the former, means adapted to control entry to and discharge of gas from said chamber through which the gas flows, and a flow-control device for the other conduit adapted to be operated by variation of pressure in said 10 other chamber.
25. In a device of the character described, in combination, two conduits in parallel connected with separate sources of gas supply for conduction of gas under pressure, means adapted to effect intermittent delivery of gas from each conduit, including a pressure operated valve operating member adapted to be exposed to the pressure in one conduit, a discharge valve for the other conduit adapted to be operated by said valve operating member, and means adapted to elastically oppose operation of said valve operating member under the pressure in said one conduit.
26. In a device of the character described, in combination, two conduits in parallel for conduction of gas under pressure, means adapted to effect intermittent delivery of gas from each conduit, including a pressure operated valve operating member adapted to be exposed to the pressure in one conduit and a discharge valve for the other conduit adapted to be operated by said valve operating member, and means whereby the pressure in said other conduit is caused to oppose operation of said valve operating member by the pressure in said one conduit.
27. In a device of the character described, in combination, two conduits in parallel for conduction of gas under pressure, automatic-pressure controlled means adapted to effect intermittent delivery of gas from each conduit, including a movable diaphragm, the opposite sides of which are adapted to be exposed to the pressure in said conduits, respectively.
28. In a device of the character described, in combination, two conduits in parallel for conduction of gas under pressure, means adapted to effect intermittent delivery of gas from each conduit, including a pressure chamber through which the gas in one conduit flows adapted to be closed against entry of gas during discharge of gas therefrom, a pressure operated valve operating member adapted to be exposed to the pressure of the gas discharged from said chamber, and a discharge valve for the other conduit adapted to be operated by said valve operating member.
29. In a device of the character described, in combination, two conduits in parallel for conduction of gas under pressure, means adapted to effect intermittent delivery of gas from each conduit, including a pressure chamber through which the gas in one conduit flows adapted to be closed against entry of gas during discharge of gas therefrom, a pressure operated valve operating member adapted to be exposed to the pressure of the gas discharged from said chamber, a discharge valve for the other conduit adapted to be operated by said valve operating member, and means adapted to elastically oppose operation of said valve operating member under the pressure of said discharged gas.
30. In a device of the character described, in combination, conduits in parallel for conduction of gas under pressure, means adapted to effect intermittent delivery of gas from each conduit, including a pressure chamber through which the gas in one conduit flows adapted to be closed against entry of gas during discharge of gas therefrom, a pressure operated valve operating member adapted to be exposed to the pressure of the gas discharged from said chamber, a discharge valve for the other conduit adapted to be operated by said valve operating member, and means whereby the pressure in the other conduit is caused to oppose operation of said valve operating member under the influence of said discharged gas.
31. In a device of the character described, in combination, two conduits in parallel for conduction of gas under pressure, means adapted to effect intermittent delivery of gas from each conduit, including a pressure chamber through which the gas in one conduit flows adapted to be closed against entry of gas during discharge of gas therefrom, a pressure operated valve operating member adapted to be exposed to the pressure of the gas discharged from said chamber, a discharge valve for the other conduit adapted to be operated by said valve operating member, and a pressure chamber through which the gas in the last mentioned conduit flows adapted to elastically oppose operation of said valve operating member under the pressure of said discharged gas.
32. In a device of the character described, in combination, two conduits in parallel for conduction of gas under pressure, means adapted to effect intermittent delivery of gas from each conduit comprising a variable volume pressure chamber through which the gas in one conduit flows, means controlled by variation of volume of said chamber adapted to close said chamber against entry of gas during discharge of gas therefrom and vice versa, a second variable volume pressure chamber through which the gas in the other conduit flows, means controlled by variation of volume of said second chamber adapted to open and close said second chamber against discharge of gas therefrom, and a third variable volume pressure chamber having a movable wall common to the wall

of said second chamber adapted to communicate with said first mentioned chamber on discharge of the latter.

33. In a device of the character described, in combination, two conduits in parallel for conduction of gas under pressure, means adapted to effect intermittent delivery of gas from each conduit comprising a variable volume pressure chamber through which the gas in one conduit flows, means controlled by variation of volume of said chamber adapted to close said chamber against entry of gas during discharge of gas therefrom and vice versa, a second variable volume pressure chamber through which the gas in the other conduit flows, means controlled by variation of volume of said second chamber adapted to open and close said second chamber against discharge of gas therefrom, and a third variable volume pressure chamber having a movable wall common to the wall of said second chamber adapted to communicate with said first mentioned chamber on discharge of the latter, said third chamber communicating with the atmosphere through the discharge port of said first mentioned conduit.

34. In a device of the character described, in combination, two conduits in parallel for conduction of gas under pressure, means adapted to effect intermittent delivery of gas from each conduit comprising a variable volume pressure chamber through which the gas in one conduit flows, means controlled by variation of volume of said chamber adapted to close said chamber against entry of gas during discharge of gas therefrom and vice versa, a second variable volume pressure chamber through which the gas in the other conduit flows, means controlled by variation of volume of said second chamber adapted to open and close said second chamber against discharge of gas therefrom, a third variable volume pressure chamber having a movable wall

common to the wall of said second chamber adapted to communicate with said first mentioned chamber on discharge of the latter, said third chamber communicating with the atmosphere through the discharge port of said first mentioned conduit, and means adapted to regulate entry of gas into said first mentioned chamber.

35. In a device of the character described, in combination, two conduits in parallel for conduction of gas under pressure, means adapted to effect simultaneous intermittent flow of gas through said conduits including a valve in one of said conduits, and a valve operating member controlled differentially by pressure in both of said conduits.

36. In a device of the character described, in combination, two conduits in parallel for conduction of gas under pressure, means controlled by pressure in one of said conduits for opening the same to flow therein, and means controlled differentially by pressures in both of said conduits for simultaneously opening the other conduit to flow therein.

37. In a device of the character described, in combination, a pressure chamber, means for closing said chamber against entry of gas during discharge therefrom, and vice versa, including a valve member, a quick-acting motor operatively connected to said valve member, pressure operated means connected to said valve member to set said motor for quick operation in either direction, and yielding means operatively associated with said valve member and being effective to yieldingly hold the same in operated position in either direction.

In testimony whereof I affix my signature, in the presence of two witnesses.

GEORGE E. HULSE.
